UNITED STATES PATENT OFFICE.

CHESTER A. SIEGEL, OF ARLINGTON, NEW JERSEY, ASSIGNOR TO AMERICAN ARCH COMPANY, A CORPORATION OF DELAWARE.

FURNACE.

Application filed August 2, 1921. Serial No. 489,828.

To all whom it may concern:

Be it known that I, CHESTER A. SIEGEL, a citizen of the United States, residing at Arlington, in the county of Hudson and State of New Jersey, have invented certain new and useful Improvements in Furnaces, of which the following is a specification.

My invention relates to furnaces and fire pans fired with fuel in gaseous, vaporous or suspended condition, and is of especial advantage for oil burning locomotives. I aim to secure thorough and intimate intermixture of fuel and air for combustion, and to improve the combustion and economy of fuel. I also aim to provide for high fuel-burning capacity in a furnace capable of efficient operation at less than its fullest capacity, so as to secure flexibility of operation sufficient to meet varied service conditions satisfactorily.

How these and other advantages can be realized through my invention will appear from my description hereinafter of the best embodiment of the invention at present known to me.

In the drawings, Fig. 1 shows a vertical longitudinal mid-section through the fire box and fire pan or flash pan of an oil fired locomotive boiler furnace embodying my invention.

Fig. 2 shows a cross-section taken as indicated by the line 2—2 in Fig. 1.

The locomotive fire box A shown in Fig. 1 is of a familiar type. It is provided with the usual sectional fire arch B extending rearward and upward from the lower portion of the tube sheet 6, and consisting of fire bricks 7 supported on fore and aft water circulation tubes 8 connected between the tube sheet 6 and the rear wall 9 of the fire box. Preferably, the arch B has a number of draft openings 10 therethrough. At the bottom of the fire box A is a fire pan structure C which may be briefly described as comprising a metal floor sheet or "shelf" 12 extending inward from the bottom of the mud ring 13, and a metal trough D with sloping sides 15, 15 extending fore and aft within and below the inner edges of the shelf 12.

The trough or fire pan D is here shown of greater length than usual, so that the shelf 12 does not extend across its forward end and is of very limited size at its rear end. As shown, also, the trough has vertical walls

16 with refractory fire brick linings or flash walls 17 at both ends, and both the flash walls 17 extend some distance upward into the fire box A, above the top of what is strictly the fire pan D. The sloping sides 15 and the flat, horizontal bottom or floor 18 of the fire pan D have refractory fire brick linings 19 such as are usual in locomotive flash pans,—as has also the shelf 12. In the floor 18, toward either end of the fire pan D are hoppers 20 of usual character. The rear walls 21 of these hoppers 20 are hinged at their upper edges, at 22 so as to swing rearward and upward.

The fire pan D is divided into fore and aft compartments 24 and 25 by an intervening refractory structure E which has the form of a transverse inverted trough covered with fire brick. In this hollow septum E are burners 27, 27, directed fore and aft into the compartments 24 and 25, toward the flash walls 17, through openings 29 in the opposite walls of said septum, and taking air for combustion therethrough. As shown, the sides 15 of the fire pan D are interrupted at the trough structure E, so as to allow free inflow of air thereto laterally as well as from beneath. The transverse refractory arch 30 which forms the top or roof of the structure E protects the subjacent burners 27 from the intense heat of combustion above,—as, indeed, does also the continual influx of cold air through the refractory structure E at the openings 29. Preferably, the supply and distribution of fuel to the burners 27, 27 is controlled by a three-way valve 31, so that either one or both of the burners can be operated and regulated or cut out at pleasure. The common supply pipe 32 may also be equipped with the usual regulating valves, etc., for oil burners of this sort.

In operation, the fuel and air jets, blasts, or streams from the burners 27, 27 are directed fore and aft against the flash walls 17 at the ends of the compartments 24 and 25, which arrest, baffle, and mix up these streams, and deflect them upward and retrovert them back toward one another above the refractory structure E, in a manner indicated by the arrows. Thus these flaming fuel streams meet beneath the fire arch B, in the upper portion or top of the combustion chamber defined by said arch. The stream from the forward directed burner 27

is deflected upward and retroverted rearward by the forward flash wall 17, and passes rearward beneath the arch B and then upward to the rear of said arch; while the 5 stream from the rearward directed burner 27 is deflected upward and retroverted forward by the rear flash wall 17, and passes forward beneath the arch B, as well as upward to the rear thereof. At and after meeting, the streams are thoroughly agitated and thrown into eddies that assure complete intermixture of them and their components of fuel and air. Further agitation and intermixture is produced by the currents from 10 the rearward stream which are drawn through the openings 10 in the arch B, and cause eddies above and below said arch.

When the forward directed burner 27 is operated alone, the flow of its stream is substantially that described above,—except, 20 that it is not deflected, agitated, and mixed up with the stream from the rearward directed burner, and hence is somewhat more regular in its course. In this case, however, 25 the draft through the rearward opening 29 causes eddies which help to agitate the fuel stream and mix it thoroughly, as well as to admix additional air with it. The action 30 with the rearward directed burner is somewhat similar in this regard; but the influences affecting the stream are more various so that greater agitation, eddying, and admixture of air occur.

What I claim is:

35 1. In a locomotive furnace, the combination of a fire arch extending from one end of the fire box toward the other; a fire pan for said fire box with a flash wall at either end thereof; and burners in said fire pan directed fore and aft toward said flash walls, so that their fuel streams shall be retroverted by said flash walls and meet in the upper portion of the combustion chamber defined by said fire arch.

45 2. In a locomotive furnace, the combination of a fire arch extending rearward from the flue sheet; a fire pan for the fire box with a flash wall at either end thereof, burners in said fire pan directed fore and aft toward said flash walls, so that their fuel streams shall be retroverted by the latter and meet in the top of the combustion chamber beneath said arch; and a refractory structure for protecting said burners from the

heat of combustion in said combustion chamber. 55

3. In a locomotive furnace, the combination of a fire arch extending rearward from the flue sheet and having draft openings therethrough; a fire pan for the fire box with a flash wall at either end thereof; and burners in the center of said fire pan directed fore and aft toward said flash walls, so that their fuel streams shall be retroverted by the latter, one forward beneath said arch, and the other rearward to meet said first mentioned stream and both upward to the rear of said arch. 65

4. In a locomotive furnace, the combination of a fire arch extending rearward from the flue sheet; a fire pan for the fire box comprising fore and aft compartments, flash walls at their opposite ends and a refractory structure separating them, and burners in said refractory structure directed fore and aft into said compartments, and taking air from combustion through openings in said structure directed fore and aft into said compartments, so that the fuel streams may meet after deflection upward at the ends of 70 said compartments. 75

5. In a locomotive furnace, the combination of a fire arch extending rearward from the flue sheet; a fire pan for the fire box comprising fore and aft compartments with flash walls at their opposite ends and a hollow refractory structure separating them, and burners in said refractory structure directed fore and aft into said compartments and taking air for combustion through said 80 structure. 85

6. A fire pan for a locomotive firebox with a transverse hollow refractory structure dividing it into fore and aft non-continuous compartments, said refractory structure having openings through its opposite walls for burners directed fore and aft into 95 said compartments.

7. A fire pan for a locomotive fire box divided into fore and aft compartments by a transverse inverted refractory trough structure with openings through its opposite walls for burners directed fore and aft into 100 said compartments.

In testimony whereof, I have hereunto 105 signed my name.

CHESTER A. SIEGEL.
